STABILIZATION OF FATS AND OILS WITH
2,5-DIHYDROXYPHENYL DIMETHYL CAR-
BINOL AND RELATED ANTIOXIDANTSAlan Bell and Donald J. Shields, Kingsport,

Serial No. 283,972

19 Claims. (Cl. 260—398.5)

1

This invention relates to the stabilization of fats, oils and other organic materials subject to deterioration employing compounds as antioxidants which are 2,5-dihydroxyphenyl (or benzyl) dialkyl (or arylalkyl) carbinols.

U. S. 2,104,084 discloses the stabilization of fats and oils with compounds which are in some instances homologs of those employed in the instant invention. However, these prior art compounds do not contain tertiary hydroxy radicals nor do they include compounds containing three hydroxy radicals, both of which characteristics contribute to the superior properties of the antioxidants of this invention.

One of the compounds disclosed as an antioxidant herein is believed to be known in the prior art only as a heading in Beilstein, volume VI, page 1124, cf. Klages, Berichte, 37, 3996 who is said to have prepared 2,5-dimethoxyphenyl dimethyl carbinol which is described as a thick oil having a high boiling point.

It is an object of our invention to provide compounds which are believed to be novel and which possess improved properties which are especially useful in the stabilization of fats and oils. Another object is to provide antioxidant compositions containing the principal antioxidants of this invention admixed with a synergist. A further object of our invention is to provide antioxidant compositions of this nature dissolved in an inert organic solvent. An additional object is to provide stabilized fats and oils containing such antioxidants and/or antioxidant compositions. A still further object of our invention is to provide processes for preparing such stabilized fats and oils. Other objects will become apparent hereinafter.

In accordance with our invention, stabilized fats and oils can be prepared which contain from about 0.001 percent to about 1.0 percent by weight of an antioxidant selected from those having the following formulas:

and

2

wherein R₁ represents a substituent selected from those consisting of an alkyl group containing from 1 to 4 carbon atoms and an aryl group of the benzene series containing from 6 to 9 carbon atoms, R₂ represents an alkyl group containing from 1 to 4 carbon atoms, and R₃ represents a substituent selected from those consisting of R₁ as defined above and a hydrogen atom.

Examples of such antioxidants included in the above formulas are 2,5-dihydroxyphenyl dimethyl carbinol, 2,5-dihydroxyphenyl diethyl carbinol, 2,5-dihydroxybenzyl dimethyl carbinol, 2,5-dihydroxybenzyl methyl ethyl carbinol, 2,5-dihydroxyphenyl methyl phenyl carbinol, 2,5-dihydroxyphenyl ethyl p-tolyl carbinol, 2,5-dihydroxybenzyl propyl xylyl carbinol, etc.

A preferred compound of the above group of antioxidants is 2,5-dihydroxyphenyl dimethyl carbinol. This compound can also be called 1-hydroxisopropylhydroquinone. It has been found that the employment of the 1-hydroxyisopropyl group on the hydroquinone nucleus results in the existence of a compound with unexpectedly advantageous antioxidant properties. As can be seen from the table which is presented hereinafter, this compound is more potent as an antioxidant than isopropyl hydroquinone. It might be theorized that this novel antioxidant is of especial value because it may be converted in situ when heated in a fat or oil being stabilized so as to form isopropenyl hydroquinone which is an exceedingly useful and potent antioxidant as described and claimed in a copending application filed on May 31, 1951, by Bell, Knowles and Tholstrup, Serial No. 229,281. In conjunction with this theoretical consideration, it would appear that the compound 2,5-dihydroxybenzyl dimethyl carbinol would also be a valuable antioxidant inasmuch as it would appear preferable that the hydroxy group be in a position alpha or beta to the benzene ring whereby an olefinic double bond in conjugated relation to the benzene ring might be formed in situ when the antioxidant is employed in a fat or oil. This latter supposition is correct and the formulas given above include such compounds. However, this does not explain the desirability of restricting the instant antioxidant compounds of our invention to those wherein the hydroxyl radical on the side chain is positioned on a tertiary carbon atom. Moreover, this does not explain the fact that we have found that the compound 2-hy-

droxy-5-methoxy-phenyl dimethyl carbinol has very little effectiveness as an antioxidant, whereas the theoretical considerations presented above indicate that the compound 2-isopropenyl-4-methoxyphenol disclosed on page 3 of a copending application filed May 31, 1951, by Bell, Knowles and Tholstrup, Serial No. 229,282, would appear to be a valuable antioxidant if it could be formed in situ. This discussion makes it evident that it is exceedingly difficult to make predictions regarding the antioxidant efficacy of compounds such as those covered by the instant invention. Consequently, it can be stated that the compounds covered by this invention which can be employed as valuable antioxidants are restricted to those wherein the hydroxy group is tertiary and is attached to the alpha or beta carbon atom to the benzene ring.

In regard to the compound 2-hydroxy-5-methoxyphenyl dimethyl carbinol which was referred to above, this compound can be prepared by reacting the methyl ester of 2-hydroxy-5-methoxybenzoic acid with methyl magnesium iodide.

The compounds of this invention which have been described above are quite useful as antioxidants for fats and oils as has been indicated. When so employed, fractions of a percent of such compounds can be incorporated into such materials as lard, cottonseed oil, peanut oil, etc., by admixing the antioxidant with the fats and oils whereby a solution of the antioxidant in the substrate is obtained. Alternatively, the antioxidant can be blended with suitable solvents to form an antioxidant solution. Examples of such solvents include glycerin and propylene glycol. Such antioxidant solutions can be more readily dissolved in the fat or oil to be stabilized with less necessity for prolonged mixing of the fat or oil with the undissolved antioxidant. Similarly, synergists can be admixed with the fats or oils along with the dry antioxidant compounds of this invention or, in order to facilitate the incorporation of the antioxidant and synergist into the fat or oil, they can both be dissolved in such solvents as propylene glycol, glycerin, hexane, etc., or other similar solvents which are inert insofar as concerns both the antioxidant and/or the synergist components in the ultimately prepared stabilized fat or oil. Examples of synergists which can be employed include citric acid, tartaric acid, phosphoric acid, ascorbic acid, etc. In addition to the employment of a single antioxidant as described hereinbefore, mixtures of two or more such antioxidants together with two or more synergists can be employed. Moreover, other antioxidants which are known in the art can be added for their supplemental effects if such be desired.

In addition to the fats and oils mentioned above which can be stabilized by the antioxidants of this invention, other representative fats and oils include linseed oil, menhaden oil, cod liver oil, castor oil, olive oil, rape seed oil, cocoanut oil, palm oil, corn oil, sesame oil, peanut oil, babassu oil, butter fat, lard, beef tallow, etc., as well as hydrogenated oils and fats prepared from any of the foregoing. Furthermore, various other oils and fats may be similarly treated within the scope of this invention. In addition, the antioxidants of this invention can be employed in certain instances to stabilize fuels, plastic compositions, etc.

A preferred procedure for preparing compounds of the type disclosed hereinabove as antioxidants

is set forth in the examples which are given below. The prior art disclosure by Klages indicates that 2,5-dimethoxyphenyl dimethyl carbinol can be prepared by the reaction of methyl magnesium iodide with 2,5-dimethoxyacetophenone. The product obtained by Klages is said to be a thick oil having a boiling point at 16 mm. Hg of 138°-141° C. It is believed that this product was actually an impure form of 2,5-dimethoxyphenyl dimethyl carbinol. Such a product would not be useful as an antioxidant since it contains no free phenolic hydroxyl radical.

The antioxidants of this invention can be prepared by a procedure which can be employed to 15 prepare 2,5-dihydroxyphenyl dimethyl carbinol as well as the other compounds related thereto. This procedure can be illustrated by the following schematic series of reactions:

The following example illustrates the preparation of 2,5-dihydroxyphenyl dimethyl carbinol:

Example 1.—2,5-dihydroxyphenyl dimethyl carbinol

A suspension of 148 parts of 2,5-dibenzoyloxyacetophenone in ethyl ether was added with stirring and cooling to an ethereal solution of methyl magnesium iodide. The latter solution was prepared from 13.5 parts of magnesium and 80.25 parts of methyl iodide. As the addition progressed a creamy precipitate appeared. The mixture was stirred for several hours and allowed to stand overnight. The mixture was then poured over a mixture of ice and excess ammonium chloride. The ether layer was separated, dried over calcium chloride, and the ether distilled to leave a residue which was recrystallized from hexane-benzene. The resulting dibenzyl ether which melted at 77° C. was obtained in a yield of 89.6 percent (137 parts).

Ten parts of the dibenzyl ether was dissolved in 125 parts of ethanol and reduced at 20-30° C. with hydrogen at 40 pounds per square inch (p. s. i.) in the presence of one part of 5 percent palladium on charcoal. The hydrogenolysis was stopped when the theoretical amount of hydrogen had been absorbed. The catalyst was removed by filtration and the ethanol was removed under nitrogen in vacuo. The resulting residue solidified and was recrystallized from hexane to give 70 3.6 parts (75 percent) of 2,5-dihydroxyphenyl dimethyl carbinol which melted at 133° C.

The product obtained in accordance with the preceding example can be employed as an antioxidant as illustrated in the table presented below wherein a number of examples are set forth of

various concentrations of this antioxidant in lard, cottonseed oil and peanut oil. These examples also include the employment of citric acid as a synergist. In addition to the employment of 2,5-dibenzoyloxyacetophenone to prepare 2,5-dihydroxyphenyl dimethyl carbinol, other related compounds can be employed to prepare the other antioxidants covered by the hereinabove set forth formulas. Thus, 1-acetonyl-2,5-dibenzoyloxybenzene can be employed in place of the 2,5-dibenzoyloxyacetophenone whereby the product obtained is 2,5-dihydroxybenzyl dimethyl carbinol. It is obvious that various other compounds can be employed in the same manner to obtain the other antioxidants described hereinbefore.

In investigating the properties of the 2,5-dihydroxyphenyl dimethyl carbinol, an attempt was made to dehydrate this compound by refluxing in benzene in the presence of a trace of iodine. Water was split out easily but the expected isopropenyl hydroquinone was not isolated in an appreciable quantity. The product obtained was a solid which melted at 193°-195° C. and which was analyzed and apparently had the formula $(C_9H_{10}O_2)_n$. It appears that the product obtained was probably the dimer.

In regard to this dehydration product of 2,5-dihydroxyphenyl dimethyl carbinol, a similar dimeric product was also obtained as one of the products produced in accordance with the following procedure:

Example 2.—Dimer from 2,5-dihydroxyphenyl dimethyl carbinol

115 parts of 2,5-dibenzoyloxyphenyl dimethyl carbinol was dissolved in ethanol and treated at 20°-30° C. with hydrogen at 40 p. s. i. (pounds per square inch) in the presence of 5 percent palladium on charcoal. Evaporation of the solvent and trituration with hexane gave 50 grams (90%) of a product. The product contained 10 percent of 2,5-dihydroxyphenyl dimethyl carbinol and the remainder was identical with the dimer obtained above by dehydrating 2,5-dihydroxyphenyl dimethyl carbinol. This product on recrystallization from benzene melted at 192°-193° C. This product had antioxidant properties as indicated by the table below. Apparently debenylation, dehydration, and dimerization occurred at the same time. The formula for this product is $(C_9H_{10}O_2)_n$ where n is probably two. The theoretical calculation is carbon 71.9%; hydrogen, 6.66%. Upon analysis it was found that the product contained 71.45 percent carbon and 6.82 percent hydrogen. A study of the struc-

ture of this dimer indicates that it may be as follows:

10 Infrared data tend to substantiate the above structure.

In addition to the preparation of the antioxidant compounds described above, the various procedures we have employed have resulted in the preparation of somewhat analogous compounds such as:

2-hydroxy-5-methoxyphenyl dimethyl carbinol

The compound 2-benzoyloxy-5-methoxyacetophenone was reacted with methyl magnesium iodide followed by debenylation with hydrogen and palladium as described in Example 1 above. The product obtained was 2-hydroxy-5-methoxyphenyl dimethyl carbinol which had a melting point at 98°-99° C. This product retained the methoxy group on the benzene ring, viz. the methoxy group was not demethylated.

The compound just described was also prepared by reacting the methyl ester of 2-hydroxy-5-methoxybenzoic acid with methyl magnesium iodide using the procedure described above in Example 1 whereby an 86.5% yield was obtained of 2-hydroxy-5-methoxyphenyl dimethyl carbinol. This product melted at 98°-99° C. The theoretical empirical formula is $C_{10}H_{14}O_3$ (65.93% carbon and 7.69% hydrogen). Upon analysis it was found that the compound obtained contained 65.94% carbon and 7.92% hydrogen on one analysis and 66.25% carbon and 7.88% hydrogen on another analysis.

40 The above results clearly indicate that the compound described in the prior art by Klages is not the same as the compound which is the preferred antioxidant of this invention.

Inasmuch as it is well known in the art to employ antioxidants in the stabilization of fats and oils, it is not believed necessary to give numerous specific examples of how the antioxidants of this invention are blended with fats or oils nor the specific proportions which can be employed in the many possible examples which would come within the scope of the description given hereinabove. The following tabulation and data is presented in order to show the properties of an antioxidant of this invention and how its properties compare with other antioxidants including those known in the prior art:

COMPARATIVE ANTIOXIDANT PROPERTIES

¹ This test conducted in lard having a control AOM value of 6.5.

The data presented above is based on tests conducted under equivalent conditions employing similar samples in each instance of cottonseed oil, peanut oil, and lard, except as indicated. The AOM figures are in hours; the symbol P. F. represents the protection factor which is the ratio of the AOM value of the stabilized substrate to that of the control which contains no antioxidant. The numbers beneath the name of the fat or oil are the peroxide values to which the sample was brought in order to determine the AOM value. The procedure employed under the AOM (active oxygen method) is well known in the antioxidant art and can be explained in this specification briefly as follows:

A weighed quantity (0.01-0.02 percent by weight) of the compound to be tested was dissolved in the lard or oil together with 0.005 percent by weight of synergist when employed. The resulting solution was placed in a bath at 99° C. (210° F.) and air then bubbled through at a rate of approximately 2.3 ml. per sec. Periodically, a portion of the test solution was removed and the peroxide content quantitatively determined by iodometric titration, expressing results as milliequivalents per kilogram of fat or oil. Experience has shown that initial rancidity in lard corresponds closely to a peroxide value of 20 and to 70 in oils such as cottonseed oil and peanut oil. The latter value has not been firmly established but is useful for comparative purposes. A control containing no additives was run simultaneously with the test compound to determine the induction period of the unstabilized material.

The final results are expressed as the number of hours required for rancidity to develop; i. e., an AOM value of 40 for a sample of lard means that 40 hr. was required to form twenty milliequivalents of peroxide per kilogram of the lard.

A perusal of this data indicates that 2,5-dihydroxyphenyl dimethyl carbinol is a superior antioxidant for fats and oils, particularly lard. Of the data presented, only propenyl hydroquinone is superior in lard; this latter compound is disclosed for the first time as an antioxidant for fats and oils in the copending application referred to above.

We claim:

1. Stabilized fats and oils containing from about 0.001% to about 1.0% by weight of an antioxidant selected from those having the following formulas:

and

wherein R₁ represents a substituent selected from those consisting of an alkyl group containing from 1 to 4 carbon atoms and an aryl group of the benzene series containing from 6 to 9 carbon atoms, R₂ represents an alkyl group containing from 1 to 4 carbon atoms, and R₃ represents a substituent selected from those consisting of R₁ as defined above and a hydrogen atom.

2. Stabilized fats and oils as defined in claim 1 wherein the antioxidant is 2,5-dihydroxyphenyl dimethyl carbinol.

3. Stabilized fats and oils as defined in claim 1 wherein the antioxidant is 2,5-dihydroxyphenyl methyl ethyl carbinol.

4. Stabilized fats and oils as defined in claim 1 wherein the antioxidant is 2,5-dihydroxyphenyl diethyl carbinol.

5. Stabilized fats and oils as defined in claim 1 wherein the antioxidant is 2,5-dihydroxybenzyl dimethyl carbinol.

10. Stabilized fats and oils as defined in claim 1 wherein the antioxidant is 2,5-dihydroxybenzyl methyl ethyl carbinol.

15. 6. Stabilized fats and oils as defined in claim 1 wherein the antioxidant is 2,5-dihydroxybenzyl methyl ethyl carbinol.

7. A process for stabilizing fats and oils which comprises admixing therewith from about 0.001% to about 0.1% by weight of an antioxidant selected from those having the following formulas:

and

wherein R₁ represents a substituent selected from those consisting of an alkyl group containing from 1 to 4 carbon atoms and an aryl group of the benzene series containing from 6 to 9 carbon atoms, R₂ represents an alkyl group containing from 1 to 4 carbon atoms, and R₃ represents a substituent selected from those consisting of R₁ as defined above and a hydrogen atom.

8. A process for stabilizing fats and oils as defined in claim 7 wherein the antioxidant is 2,5-dihydroxyphenyl dimethyl carbinol.

40. 9. A process for stabilizing fats and oils as defined in claim 7 wherein the antioxidant is 2,5-dihydroxyphenyl methyl ethyl carbinol.

10. A process for stabilizing fats and oils as defined in claim 7 wherein the antioxidant is 2,5-dihydroxyphenyl diethyl carbinol.

45. 11. A process for stabilizing fats and oils as defined in claim 7 wherein the antioxidant is 2,5-dihydroxybenzyl dimethyl carbinol.

12. A process for stabilizing fats and oils as defined in claim 7 wherein the antioxidant is 2,5-dihydroxybenzyl methyl ethyl carbinol.

50. 13. Stabilized fats and oils containing from about 0.0005% to about 0.05% by weight of a synergistic acid selected from the group consisting of citric acid, tartaric acid, phosphoric acid, ascorbic acid, alanine and cysteine and from about 0.001% to about 0.1% by weight of an antioxidant selected from those having the following formulas:

and

wherein R₁ represents a substituent selected from those consisting of an alkyl group containing from 1 to 4 carbon atoms and an aryl group of the benzene series containing from 6 to 9 carbon atoms.

atoms, R₂ represents an alkyl group containing from 1 to 4 carbon atoms, and R₃ represents a substituent selected from those consisting of R₁ as defined above and a hydrogen atom.

14. Stabilized fats and oils containing from about 0.0005% to about 0.05% by weight of citric acid and from about 0.001% to about 0.1% by weight of an antioxidant selected from those having the following formulas:

and

wherein R₁ represents a substituent selected from those consisting of an alkyl group containing from 1 to 4 carbon atoms and an aryl group of

the benzene series containing from 6 to 9 carbon atoms, R₂ represents an alkyl group containing from 1 to 4 carbon atoms, and R₃ represents a substituent selected from those consisting of R₁ as defined above and a hydrogen atom.

15. Stabilized fats and oils as defined in claim 14 wherein the antioxidant is 2,5-dihydroxyphenyl dimethyl carbinol.

16. Stabilized fats and oils as defined in claim 10 14 wherein the antioxidant is 2,5-dihydroxyphenyl methyl ethyl carbinol.

17. Stabilized fats and oils as defined in claim 14 wherein the antioxidant is 2,5-dihydroxyphenyl diethyl carbinol.

18. Stabilized fats and oils as defined in claim 14 wherein the antioxidant is 2,5-dihydroxybenzyl dimethyl carbinol.

19. Stabilized fats and oils as defined in claim 14 wherein the antioxidant is 2,5-dihydroxybenzyl methyl ethyl carbinol.

ALAN BELL.

DONALD J. SHIELDS.
